CLAIM

I claim the ornamental design for a hair styling device, as shown and described.

DESCRIPTION

FIG. 1 is a top plan view of a hair styling device in accordance with the present invention;

FIG. 2 is a side elevation of the back side of the hair styling device shown in FIG. 1;

FIG. 3 is a bottom plan view of the hair styling device shown in the previous figures;

FIG. 4 is a side elevation view of the hair styling device taken from the right side of the previous figures, the left side being the mirror image thereof; and,

FIG. 5 is a side elevation view of the front side of the hair styling device shown in the previous figures.
